UNITED STATES PATENT OFFICE.

PETER J. LEITHAUSER, OF DEFIANCE, OHIO.

PUMP.

Application filed August 29, 1924. Serial No. 734,981.

This invention aims to provide an improvement in pumps especially designed for use in wells and adapted to produce the flow of a maximum amount of water in a practically continuous stream during the operation of the pump, the pump operating in such a novel and effective manner as to have a high degree of efficiency.

A further object is to provide a pump of this character and having these advantages and wherein a single plunger operates in conjunction with an arrangement providing in effect two working chambers.

A further object is to provide a pump of the character specified which is of simple and durable construction, reliable and efficient in operation and adapted to be manufactured in accordance with conventional practice and from materials and by means of facilities ordinarily available.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view partly in section and partly in elevation showing a well pump embodying the present invention, and

Figure 2 is an enlarged view partly in section and partly in elevation showing the details of the valve plunger or traveling valve.

In the drawings, a well casing is designated at 5 and has a head 6 at its upper end on which a pump pipe or flow line designated generally at 7 is supported. This pump pipe or flow line 7 is made up of a number of tubular sections suitably coupled to each other. A tubular member 8 is coupled to the lower end of the flow line 7 and provides a working chamber as will hereinafter appear. To the lower end of the tubular member 8 a working barrel 9 is connected and has a standing valve 10 in its lower end which provides a valve controlled inlet into the lower end of the working barrel.

A valved plunger or travelling valve 11 is operatively fitted in the working barrel 9. This plunger 11 is shown to advantage in Figure 2 and the passage which extends therethrough is controlled by a downwardly seating check valve 12. The upward move-

ment of the valve 12 is limited by means of stops 13 provided on a combined valve cage and coupling 14. A hollow plunger rod 15 has its lower end threaded into the combined valve cage and coupling 14 and the opening of this hollow plunger rod 15 communicates with the passage extending through the plunger 11 at a point above the valve 12 as shown in the drawings. The upper end of the hollow plunger rod 15 is connected with a sucker rod 16 as indicated at 17. The sucker rod 16 operates through a stuffing box 18^a provided in a cap 18 fitted on the upper end of the pump pipe or flow line 7 and this sucker rod may be reciprocated from a handle 19 having a pin and slot connection 19^a therewith or it may be reciprocated from a windmill or from any suitable source of power.

A partition 20 is interposed between the lower end of the pump pipe or flow line 7 and the upper end of the working chamber 8 and centrally this partition 20 is provided with a stuffing box 21 through which the hollow plunger rod 15 is slidably fitted. In this manner direct communication between the working chamber and the pump pipe or flow line 7 is prevented.

An inlet pipe 22 communicates with the upper end of the working chamber 8 by means of an elbow 23 or other suitable fitting and in the lower end of the inlet pipe 22 a standing valve 24 is provided in order that a valve controlled inlet may be had.

A check valve controlled port 25 is provided in that portion of the hollow plunger rod 15 which works within the chamber 8 and the working barrel 9.

An offtake pipe 26 leads from adjacent the upper end of the pump pipe or flow line 7 to the storage tank or point of distribution and may have a valved discharge spout 27 incorporated therein.

In operation when the plunger 11 moves downwardly liquid is drawn into the working chamber 8 through the inlet pipe 22 and liquid that has been previously drawn into the working barrel below the plunger is expelled up through the plunger and through the hollow plunger rod into the flow line 7 at this time and during this movement. On the upstroke of the plunger 11 liquid is drawn into the working barrel 9 below the plunger and simultaneously liquid is expelled from the chamber 8 through the check valve controlled port 25 and hollow plunger

rod 15. The partition 20 and the valves 12 and 25 prevent back flow of the liquid from the flow line.

I claim:

5. 1. A pump of the character described comprising a working barrel having a valve controlled inlet at its lower end, a working chamber separate and distinct from and directly above and vertically aligned with the working barrel, the lower end of the working chamber being open and having free, open and direct communication with the upper open end of the working barrel, the lower end of said working chamber being secured to the upper end of said working barrel, a valve controlled inlet to the working chamber, a plunger operating in said working barrel only, said plunger having an opening extending therethrough and also 10 having a downwardly seating check valve controlling the flow of liquid through the opening and an elongated hollow plunger rod having its lower end fixedly connected to the plunger and also having its lower end in free, direct and open communication with the 15 plunger above the downwardly seating check valve thereof, said hollow plunger rod receiving the discharge from the plunger, the downwardly seating check valve preventing back flow from the plunger rod, a short tubular inlet valve casing connected to the plunger rod and extending laterally therefrom, said inlet valve casing being connected to such portion of the plunger rod as to operate in the working chamber, said inlet valve casing communicating at its inner end with the interior of the plunger rod and having a port at its outer end in communication with the interior of the working chamber, a spring closed 20 check valve operable with the port of the inlet valve casing, said spring closed check valve seating outwardly and serving to permit fluid to flow from the working chamber through the inlet valve casing into the hollow plunger rod while precluding the fluid from flowing from the plunger rod back into the working chamber and a flow line receiving the discharge from the plunger rod. 25
2. A pump of the character described comprising a working barrel having a valve controlled inlet at its lower end, a working chamber separate and distinct from and directly above the working barrel, the lower end of the chamber being open and having free, open and direct communication with the upper open end of the working barrel, the lower end of said chamber being secured to the upper end of the working barrel, a valve controlled inlet to the working chamber, a plunger operating in said working barrel only, said plunger having an opening extending entirely therethrough and also 30 having a downwardly seating check valve controlling the flow of liquid through its opening, an elongated plunger rod, a combined valve cage and coupling between the lower end of the plunger rod and the plunger serving to couple these parts and to afford direct communication between the plunger rod and the plunger, said combined valve casing and coupling having stops limiting the upward movement of the valve of the plunger, said hollow plunger receiving the discharge from the plunger, the downwardly seating check valve preventing back flow from the plunger rod, said plunger rod having a laterally extending port provided with a laterally movable and outwardly seating check valve so as to permit the fluid to flow from the working chamber into the plunger rod, but to prevent back flow from these parts and a flow line receiving the discharge from the hollow plunger rod. 35
3. A pump of the character described comprising a working barrel having a valve controlled inlet at its lower end, a working chamber separate and distinct from and directly above the working barrel, the lower end of the chamber being open and having free, open and direct communication with the upper open end of the working barrel, the lower end of said chamber being secured to the upper end of the working barrel, a valve controlled inlet to the working chamber, a plunger operating in said working barrel only, said plunger having an opening extending entirely therethrough and also 40 having a downwardly seating check valve controlling the flow of liquid through its opening, an elongated plunger rod, a combined valve cage and coupling between the lower end of the plunger rod and the plunger serving to couple these parts and to afford direct communication between the plunger rod and the plunger, said combined valve casing and coupling having stops limiting the upward movement of the valve of the plunger, said hollow plunger receiving the discharge from the plunger, the downwardly seating check valve preventing back flow from the plunger rod, said plunger rod having a laterally extending port provided with a laterally movable and outwardly seating check valve so as to permit the fluid to flow from the working chamber into the plunger rod, but to prevent back flow from these parts and a flow line receiving the discharge from the hollow plunger rod. 45

PETER J. LEITHAUSER.
